(57) **CLAIM**

The ornamental design for an expandable melon storage container, as shown and described.

DESCRIPTION

FIG. 1 is a front perspective view of an expandable melon storage container depicted in an expanded state, showing our new design;

FIG. 2 is a front view thereof with a rear view being the mirror image;

FIG. 3 is a left side view thereof with a right side view being the mirror image;

FIG. 4 is a top view thereof;

FIG. 5 is a bottom view thereof;

FIG. 6 is a front view of the expandable melon storage container depicted in a collapsed state with a rear view being the mirror image;

FIG. 7 is a left side view thereof with a right side view being the mirror image;

FIG. 8 is an exploded perspective view of the expandable melon storage container depicting a top member in an expanded state;

FIG. 9 is an exploded front view thereof with a rear view being the mirror image;

FIG. 10 is a top view thereof with the top shown separately from the base; and,

FIG. 11 is bottom view of the top member of the expandable melon storage container.
